UNITED STATES PATENT OFFICE

ANDREW B. CLARK, OF THOMASVILLE, GEORGIA, ASSIGNOR OF ONE-HALF TO ROSCOE LUKE, OF THOMASVILLE, GEORGIA

DOORCHECK

Application filed October 15, 1929. Serial No. 399,779.

This invention aims to provide novel means whereby a door will be closed, after it has been opened, and whereby the closing movement of the door will be checked.

It is within the province of the disclosure to improve generally, and to enhance the utility of, devices of that sort to which the present invention appertains.

With the above and other objects in view, which will appear as the description proceeds, the invention resides in the combination and arrangement of parts and in the details of construction hereinafter described and claimed, it being understood that changes may be made in the precise embodiment of the device herein disclosed, within the scope of what is claimed, without departing from the spirit of the invention.

In the accompanying drawings:

Figure 1 shows in elevation, a device of the class described, mounted on a door;

Figure 2 is a horizontal section wherein the device claimed appears in top plan;

Figure 3 is an elevation showing the tank and the telescopic arm;

Figure 4 is a longitudinal section through the tank and parts therewithin;

Figure 5 is a transverse section on an enlarged scale on the line 5—5 of Figure 4;

Figure 6 is a transverse section on the line 6—6 of Figure 4;

Figure 7 is a transverse section on the line 7—7 of Figure 4.

The numeral 1 marks a door frame, and the numeral 2 marks a door or other closure hinged at 3 to the frame 1 for horizontal swinging movement. A vertical, cylindrical tank 4 is secured at 5 to the door frame 1. The tank 4 is so called because it contains oil or other lubricant that is not shown. A cylinder 6 is secured within the tank 4. The cylinder 6 has longitudinal guide slots 7. There is a compartment 8 in the bottom of the cylinder 6. First ports 9 are located in

the lower part of the cylinder 6 and establish communication between the compartment 8 on the one hand, and the space between the cylinder 6 and the tank 4 on the other hand. In the bottom of the cylinder 6 there are second ports 10. The ports 10 establish com-

munication between the compartment 8 and the interior of the cylinder 6. The ports 10 are closed by a valve 11, such as a metal ring, mounted to slide in the cylinder 6, and to seat on the bottom of the cylinder, about a neck 12 which upstands from the bottom of the cylinder. A valve casing 14, preferably in the form of a tube, is mounted in the bottom of the cylinder 6, in the bottom of the tank 4, and in the neck 12.

The valve casing 14 extends across the compartment 8 and has a longitudinal bore 15. The valve casing 14 is provided with a transverse opening 16 communicating with the bore 15 and with the compartment 8. The numeral 17 designates a screw threaded into the outer end of the valve casing 14. The screw 17 may be advanced or retracted, so as to shut off the transverse opening 16, more or less, and on this account, the screw 17 constitutes a valve under the control of an operator.

A piston 18 slides in the cylinder 6, and may be provided with a packing 26, of any desired kind. The piston 18 has lateral pins or projections 19 which are received slidably in the guide slots 7 of the cylinder 6. The construction is such that although the piston 18 has right line sliding movement in the cylinder 6, the piston cannot rotate in the cylinder.

A compression spring 20 is disposed in the tank 4, about the cylinder 6. The upper end of the spring 20 abuts against the top of the tank 4, and the lower end of the spring abuts against the projections 19 on the piston 18.

A plunger 21, in the form of a screw, is mounted for rotation in the top of the tank 4. The screw 21 has a helical thread 22 engaged with the piston 18. The upper end of the screw or plunger 21 is connected at 24 to a longitudinally extensible telescopic arm 23, which is pivoted at 25 to the door 2.

When the door 2 is opened, the telescopic arm 23 is swung horizontally, and rotation is imparted to the screw 21. The piston moves upwardly because the plunger or screw 21 is threaded at 22 into the piston 18, and because the pins 19 and the guide

100

slots 7 constrain the piston 18 to right-line sliding movement in the cylinder 6.

When the piston 18 moves upwardly, the spring 20 is compressed, because the spring

5 is engaged between the pins 19 on the piston

18 and the upper end of the tank 4.

When the piston 18 moves upwardly, as aforesaid, oil is sucked into the lower end of the cylinder 6, through the ports 9, the compartment 8 and the second ports 10. Oil, also, passes into the lower end of the cylinder through the transverse opening 16 and the bore 15 of the valve casing 14. The valve ring 11 rises and permits the oil to pass through the ports 10, as aforesaid.

When the door 2 is released, the spring 20 shoves the piston 18 downwardly and rotation is imparted to the plunger 21, because the piston 18 is threaded at 22 upon the 20 plunger 21, the piston 18 being held for downward right line sliding movement, because the pins 19 of the piston are received slidably in the guide slots 7 of the cylinder 6.

When the plunger 21 is rotated by the downward movement of the piston 18, the arm 23 is swung horizontally, and the door 24 is closed.

When the piston 18 starts to move downwardly, the ring valve 11 moves downwardly to the position of Figure 4, and closes the ports 10. Oil can now pass out of the lower portion of the cylinder 6 only through the bore 15 of the tubular valve casing 14, and the piston 18, consequently, descends very slowly under the action of the spring 20, the closing movement of the door 2 being retarded accordingly. The speed with which the door 2 closes can be regulated by threading the screw 21 up or down, so that the transverse opening 16 in the valve casing 14 will be closed, more or less.

What is claimed is:

45 1. A door check and closer comprising a cylinder, a piston slideable in the cylinder, a member connected to the piston, means for connecting said member to a closure, and means for imparting sliding movement to the piston when said member is rotated by the closure, the cylinder having a compartment
50 at its lower end, provided with an inlet and outlet, means for regulating at the will of an operator the flow from the compartment to the cylinder, the base of the cylinder having ports establishing communication between
55 the cylinder and the compartment, and a ring valve slideable in the cylinder and controlling the ports, the base of the cylinder having an upstanding neck which engages within the ring valve to aid in centering the ring valve
60 as the ring valve seats on the ports.

as the ring valve seats on the ports.

2. A door check and closer, constructed as set forth in claim 1, and further characterized by the provision of a packing on the lower end surface of the piston and having an additional function, in that it acts as a cushion engag-

ing the ring valve, when the ring valve closes the ports in the base of the cylinder and when the piston moves down on top of the ring valve.

3. A door check and closer comprising a 70

tank, a cylinder in the tank and having longitudinal guide slots, a piston slideable in the cylinder, a member threaded into the piston, means for connecting said member to a closure to secure rotation of said member, lateral projections on the piston and extended into the tank through the guide slots, a compression spring in the tank, the projections forming an abutment for the spring and forming, also, a means for holding the piston against rotation, and means for establishing communication between the tank and the cylinder. 75 80

4. In a door check and closer which embodies a tank, a cylinder in the tank and having its lower end in direct contact with the lower end of the tank, a piston slideable in the cylinder, means for holding the piston against rotation, a member threaded into the piston, and means for connecting said member to a closure: an improved valve mechanism which enables the lower end of the cylinder to be in direct contact with the lower end of the tank, as aforesaid, said valve mechanism comprising an automatically acting valve in the cylinder below the piston and controlling a port communicating with a compartment in the cylinder above the said lower end of the cylinder, the cylinder having a side port establishing communication between the compartment and the interior of the tank, a valve casing mounted in said lower end of the tank and mounted in the cylinder at a point above the compartment and aiding in holding said lower ends of the cylinder and the tank in direct contact, the casing having a longitudinal bore communicating with the cylinder above the compartment and below the piston, the casing having a transverse opening communicating with the compartment and the bore, and a valve under the control of an operator and located in the bore, the last-specified valve controlling the transverse opening. 110

In testimony that I claim the foregoing as my own, I have hereto affixed my signature. 115

ANDREW B. CLARK.
